ABSTRACT

A screw profile machine for compressible media, in which the profile of the head of the lobes of a driving rotor is formed by two portions of epicycloids interconnected by a conjugating curve. The rear portion of the conjugating curve, as viewed in the direction of the driving rotor rotation, is a portion of an elongated hypocycloid formed as a result of oscillations of a generating circumference along the inner side of the initial circumference of the driving rotor with a point disposed outside the generating circumference whose radius is greater than zero but is smaller than the radius of the initial circumference of the driving rotor, and the front portion of the conjugating curve, as viewed in the direction of the driving rotor rotation, is essentially an arc of a circumference.

SCREW ROTOR MACHINE FOR COMPRESSIBLE MEDIA

BACKGROUND OF THE INVENTION

The present invention relates to devices for compressing compressible media, or for converting the energy of compressed media into a mechanical one and, more particularly, to screw rotor machines.

Known in the art is a screw rotor machine comprising a body and driving and driven rotors installed in the body and interacting with each other and the body. The profile of the head of the lobe of the driving rotor is formed in its butt end section by two portions of epicycloids interconnected by a conjugating curve, with the front portion of the lobe head, as viewed in the direction of the driving rotor rotation, being formed by a part of the epicycloid and a conjugating curve which is essentially an arc of a circumference with its center disposed on an initial circumference of the driving rotor, and the rear portion of the lobe head being formed by a part of the epicycloid.

The profile of the flank of the lobe of the driven rotor is conjugated with respect to the profile of the head of the lobe of the driving rotor.

Compression of the gas in the machine is due to a decrease in the volume of spaces isolated from the suction pipe branch. These spaces are confined by the surfaces of the driving and driven rotors and the surface of the body which is essentially a surface of two straight intersecting cylinders having parallel axes.

To hermetically seal the spaces of the rotors at the moments when the medium is supplied and discharged, it is necessary that the surfaces of the rotors and the body should contact each other, and the total line of the contact should be continuous.

The conventional machine is disadvantageous in that there are jammed volumes at the sides of the medium supply and discharge, which are formed in the case of a continuous line of contact. The jammed volumes result in the formation of pulsating loads acting on the bearings and synchronizing gears, and decrease the efficiency and reliability of the machine.

Another disadvantage of the machine lies in the fact that the area confined by the lines of the rotors engagement exceeds the area of the cavity between the adjacent lobes of the driven rotor. This results in the driven rotor being loaded with a torque constituting approximately 20 percent of the turning moment applied to the driving rotor of the machine, and decreases the reliability of the machine.

An object of the present invention is to provide a screw rotor machine, in which the profile of the head of the lobe of the driving rotor ensures a decrease of the jammed volumes and unloading of the driven rotor of the turning moment.

SUMMARY OF THE INVENTION

This object is accomplished in that in a screw rotor machine for compressible media, according to the invention, the rear portion of a conjugating curve, as viewed in the direction of the driving rotor rotation, is essentially a part of an elongated hypocycloid formed in the course of oscillation of a generating circumference along the inner side of the initial circumference of the driving rotor with a point disposed outside the generating circumference whose radius is more than zero but is smaller than the radius of the initial circumfer-

ence of the driving rotor, and the front portion of a conjugating curve, as viewed in the direction of the driving rotor rotation, is essentially an arc of a circumference.

5 It is expedient that a center of the arc of the circumference be disposed inside the generating circumference of the driving rotor.

BRIEF DESCRIPTION OF THE DRAWING

10 The following description of an exemplary embodiment of the present invention is given with reference to the accompanying drawing which diagrammatically shows a cross section of a screw rotor machine according to the invention.

DETAILED DESCRIPTION OF THE INVENTION

A screw rotor machine has driving and driven rotors 2 and 3 respectively mounted in a body 1. Lobes 4 of the driving rotor 2 consist mainly of heads only, while lobes 5 of the driven rotor 3 consist mainly of legs or flanks only. The number of the lobes 4 of the driving rotor 2 should not be less than two and the number of lobes 5 of the driven rotor 3 less than three.

In the butt end section, the profile of the head of the 25 lobe 4 of the driving rotor 2 is not symmetrical to a radial line described to the peak of lobe D₁, and is formed by two portions A₁C₁ and A₁'C₁' of epicycloids, portion C₁D₁ of an elongated hypocycloid and arc C₁'D₁ of the circumference.

30 The rear portion of the lobe 4, as viewed in the direction of the driving rotor 2 as indicated by the arrow, is formed by portion A₁C₁ of the epicycloid and portion C₁D₁ of the elongated hypocycloid. The front portion of the lobe 4, as viewed in the direction of rotation of the driving rotor 2, is formed by portion A₁'C₁' of the epicycloid and arc C₁'D₁ of the circumference.

The epicycloids A₁C₁ and A₁'C₁' are formed as a result of oscillation of a generating circumference 6 along the outer side of an initial circumference 7 of the driving rotor 2. Describing points A₂ and A₂' are disposed on the generating circumference 6.

The portion of the elongated hypocycloid C₁D₁ is formed as a result of the oscillation of a generating circumference 8 along the inner side of the initial circumference 7 of the driving rotor 2 by describing point S spaced from the center of the generating circumference 8 over a distance equal to the sum of the height of the head of the lobe 4 and the radius of the generating circumference 8.

50 The line of engagement of the driving and driven rotors 2 and 3 respectively is closed and is formed by curves which are essentially trajectories of points A₂ and S₁.

55 The arc C₁D₁ is formed by a radius which is smaller than the radius of circumference 9 of the projections of the driving rotor 2.

When the radius forming the arc C₁D₁ is of a certain length, the epicycloid C₁'D₁' may have no portion on the front side of the lobe 4 and the profile of the latter is formed in this case by the following three curves: a portion of the epicycloid A₁C₁, a portion of the elongated hypocycloid C₁D₁ and the arc of the circumference C₁'D₁.

60 The radius of the arc C₁'D₁ of the circumference may exceed the height of the head of the lobe 4, in which case the center of the arc C₁'D₁ will be disposed inside the initial circumference 7 of the driving rotor 2.

During the screw rotor machine operation the medium filling up the spaces confined by the surfaces of the driving and driven rotors 2 and 3 and the surface of the body 1 changes its volume in the course of rotation of said rotors and is moved from the inlet pipe branch of the screw machine to the outlet pipe (not shown in the drawing).

Hence, due to the fact that the profile of the head of the lobe 4 of the driving rotor 2 consists of a portion of an elongated hypocycloid and an arc of a circumference smoothly joined to each other and to the portions of the epicycloids, and is oriented relative to the compressors so that the rear portion of the head of the lobe, as viewed in the direction of rotation of the driving rotor, is formed by portions of an elongated hypocycloid and epicycloid, there is provided a decrease in the jammed volumes at the side of the inlet and outlet of the screw rotor machine, thereby resulting in decreased pulsating loads acting on the bearings and synchronizing gears and increased efficiency of the process of compression (expansion) of the medium and higher reliability of the machine.

In addition, in the present screw rotor machine, the difference between the area confined by the line of engagement of the lobes of the rotors and the area of the cavity of the driven rotor in the butt end section is decreased, as a result of which the driven rotor is relieved of the turning moment and the contact stresses between the lobes of the rotors or, in the case of employment of synchronizing gears, the contact stresses acting on the teeth of the gears are reduced, thus promoting a greater reliability of the machine operation.

With the center of the arc of the circumference forming the front portion of the profile of the head of the lobe disposed inside the initial circumference of the driving rotor, the driven rotor is completely relieved of the turning moment.

The profile of a lobe is understood as a line along

which the surface of the lobe intersects the plane perpendicular to the axis of rotor rotation. The head of a lobe is a part of the lobe profile located beyond the limits of the initial circumference 7 of the rotor 2. The location of the curves A_1C_1 , C_1D_1 , D_1C_1' and $C_1'A_1'$ on the profile of a lobe head and their orientation relative to the direction of rotation determines the quality of the rotors as working components of screw rotor machines. This necessitates the use of the terms "the front portion" and "the rear portion" of a lobe (in the direction of rotation).

What is claimed is:

1. A screw rotor machine for compressible media, preferably a compressor, comprising a body; a driving rotor mounted in said body; at least one driven rotor mounted in said body and coaxial with said driving rotor, said driving rotor having an initial circumference and at least two lobes extending from the initial circumference, each lobes having a profiled head defined by two portions of epicycloids interconnected by a conjugating curve, a rear portion of said curve, as viewed in the direction of said driving rotor rotation, being essentially a portion of an elongated hypocycloid formed as a result of oscillation of a generating circumference along the inner side of the initial circumference of said driving rotor with a point disposed outside said generating circumference whose radius is greater than zero but is smaller than the radius of said initial circumference of said driving rotor, and a front portion of said conjugating curve, as viewed in the direction of said driving rotor rotation, being essentially an arc of a circumference.

2. The screw rotor machine as claimed in claim 1, in which the center of said arc of the circumference is disposed inside said initial circumference of the driving rotor.
